UNITED STATES PATENT OFFICE

HERMAN HERRENBRUCK, OF BELLEVILLE, ILLINOIS, ASSIGNOR TO ORBON STOVE CO., OF BELLEVILLE, ILLINOIS, A CORPORATION OF DELAWARE

OVEN DOOR CONSTRUCTION

Original application filed August 3, 1928, Serial No. 297,178. Divided and this application filed April 8, 1929. Serial No. 353,455.

This invention relates to oven door construction, and an object is to provide an oven door and a door frame assembled in a novel relationship and including an improved device for controlling the opening and closing of the door and to limit extent of movement of the door toward open position.

Another object of the invention is to provide an oven door having novel pivotal supports and a spring retarder connected to one of the pivotal supports and cooperating therewith to control movement of the door toward open position.

Other objects will appear from the following description, reference being made to the drawings in which

Fig. 1 is an inside elevation of the oven door and frame.

Fig. 2 is a sectional view approximately on the line 2—2 of Fig. 1.

Fig. 3 is a front elevation of the part of the oven wall and door frame and door.

Fig. 4 is a detail view showing means for stopping and supporting the oven door in approximately horizontal open position.

The front wall 1 of the oven has an opening therethrough which is surrounded by a rigid door frame 2. This rigid door frame 2 is integrally or rigidly supported inwardly from the inner surface of the wall 1 by an inwardly extending flange 3. This provides a construction in which the door 4 can be received within the opening in the wall 1 and in such position is surrounded by the flange 3 and seats against the frame 2. The door 4 has on one lower corner a laterally projecting hinge 5. The hinge 5 projects through a hole 6 in the flange 3 under a stop abutment lug 7 rigid with the wall 1 and having an inclined surface 8 which is designed and adapted to be engaged by the face 9 of a lug 10 when the door is swung outwardly and downwardly to approximately horizontal position and thereby support the door.

45 A projection 11 extends laterally from the opposite lower corner of the door in axial alignment with the projection 5 and forms a hinge for the opposite end of the door. An arm 12 extending angularly from the projection 11 is connected by a pivot 13 with a fork

14 on the lower end of a rod 15. The upper end of the rod 15 extends for sliding movements through a guide bracket 16 rigid with the wall 1 adjacent to the flange 3. The bracket 16 is attached to the wall 1 by a removable screw 17, the threaded end of which is received in a thickened portion 18 of the wall 1 so that no part of the screw is exposed on the outside of the wall. A spring 19 encircles the rod 15 and has its lower end abutting against the fork 12 and its upper end against the bracket 16, thus tending to hold the door 4 closed but yielding to permit the door to open.

That part of the wall of the oven that operates with the projection 11 comprises a removable panel 20 fitting in an opening provided therefor at the corner of the door opening. The lower end of the flange 3 at this side of the door opening terminates above the projection 11 so that when the panel 20 is not in place there is sufficient room to permit the projection 11 and the arm 12 to be passed laterally through the opening that is finally covered by said panel 20 and properly located to cooperate with the projection 5 to function as a hinge for the lower edge of the door. When these parts are properly located the panel 20 is secured in position by engaging a projection 21 at the upper end of the panel against the inside of the adjacent portion of the wall 1 and, by fastening the lower end of the panel to the wall by means of a screw 22. This screw 22 is removable and passes through the marginal portion of the wall 1 and into an adjacent thickened portion of the panel 20 so that no part of said screw is exposed on the outside. A vertical flange 23 on the edge of the panel 20 that is adjacent to the flange 3 is formed with a notch 24 to receive the hinge projection 11. The edge of the panel 20 that is adjacent to the edge of the door 4 is approximately in alignment with the surface of the flange 3 that is adjacent to the door 4. The width of the panel 20 is somewhat greater than the length of the projection 11 so that the opposite edge of the panel 20 is beyond the end of the projection 11 and beyond the arm 12, in order to permit outward movement of the pro-

jection 11 and arm 12 when the panel 20 is removed.

When the door is assembled in this manner the hinge projections 5 and 11 are pivotally connected with the oven wall so as to permit the door to be opened and closed. The door is received within the opening bordered by the flange 3 and is thereby held from endwise movement in either direction, but may be freely opened and closed.

10 The present subject matter is divided from my prior application Serial No. 297,178, filed August 3, 1928.

15 The construction, arrangement and relationship of the parts may be varied within equivalent limits without departure from the nature and principle of the invention. I do not restrict myself in any unessential respects, but what I claim and desire to secure by Letters Patent is:—

20 1. In a stove, a wall having a door opening, flanges extending inwardly along the margins of the door opening and having holes therethrough at the lower corners of the door opening, a door seating frame rigid with said flanges, a door mounted in said opening for movement to and from position against said frame, a projection rigid with one lower corner of said door extending laterally through one of said holes beyond said opening and engaging the inner side of said wall and forming a pivot for said corner of said door, a rigid abutment engaged by said projection when the door is swung outwardly and downwardly, a removable panel at the opposite corner of said opening, a projection from said door in axial alinement with said first projection engaging the inner side of said panel and cooperating with said first projection to permit the door to be swung to open and closed positions, and means for holding said panel in position.

25 2. In a stove, a wall having a door opening, flanges extending inwardly along the margins of the door opening and having holes therethrough at the lower corners of the door opening, a door seating frame rigid with said flanges, a door mounted in said opening for movement to and from position against said frame, a projection rigid with one lower corner of said door extending laterally through one of said holes beyond said opening and engaging the inner side of said wall and forming a pivot for said corner of said door, a rigid abutment engaged by said projection when the door is swung outwardly and downwardly, a removable panel at the opposite corner of said opening, a projection on the adjacent corner of said door in axial alinement with said first projection and engaging the inner side of said panel and forming a pivot cooperating with said first named pivot and permitting the door to be swung to open and to closed positions, a device extending outwardly through said wall

and extending into said panel and holding said panel in position, and resilient means cooperating with said second projection resisting the movement of the door to open position and assisting in closing the door.

70

3. In a stove, an oven wall having a door opening therethrough, a rigid door frame surrounding said opening and having an opening through one of the sides thereof at one of its lower corners, a panel for closing said corner opening in said frame and having a hole extending outwardly and terminating short of the outer surface of said panel, a fastener extending outwardly through said wall and engaging in said hole and having its outer portion entirely covered by said panel and clamping said panel against said wall, and a projection on the opposite end of said panel from said fastener extending against the inner side of said wall.

80

4. In a stove, an oven wall having an opening therethrough, a rigid door frame around said opening and having an opening through one side thereof at one of the lower corners of said frame, a panel for closing said opening and having a thickened portion at its lower end seated against the outer surface of the wall, a fastener extending outwardly through said wall and terminating in and being enclosed by said thickened portion of said panel and fastening said panel in position, and a projection on the upper end of said panel extending against the inner surface of said wall and cooperating with said fastener to hold said panel rigidly in position.
